(57) CLAIM

The ornamental design for a purse, as shown and described.

DESCRIPTION

A portion of the disclosure of this patent document contains material to which a claim for copyright is made. The copyright owner has no objection to the facsimile reproduction of the patent document or the patent disclosure, as it appears in the Patent and Trademark Office patent file or records, but reserves all other copyrights whatsoever.

FIG. 1 is a perspective view of another alternative embodiment of a purse embodying our new design, with unclaimed portions of the purse shown in broken lines;

FIG. 2 is a front elevational view of the purse of FIG. 1; and, FIG. 3 is a rear elevational view of the purse of FIG. 1. The broken line portions of the disclosure are for illustrative purposes only and form no part of the claimed design.

1 Claim, 3 Drawing Sheets
